PROCESS AND MEANS FOR RESOLING
SHOES

John C. Dobyne, St. Louis, Mo.

Application July 12, 1929. Serial No. 377,714

16 Claims. (Cl. 12—142)

This invention relates to a process of resoling shoes.

In the process of resoling shoes as heretofore practiced, it has been the custom to remove the forepart of the outsole and then replace that part by another half sole, which is suitably secured to the upper as by stitching or metallic fasteners. In such a process, however, neat work is not secured even though the shank part of the old sole remaining be secured to the half sole by chamfering, fasteners or cement. Moreover, such an arrangement is a rather weak construction, for the reason that there is always a tendency to break the joint between the sole parts at the shank and forepart. The replacement of the entire sole by another one is a difficult operation, as it is practically impossible to secure the required shape at the shank with the ordinary tools accessible to the repairmen. The simple laying of an outsole over the old sole results in a cumbersome sole of double thickness, which will not have the desired neatness of appearance.

One of the objects of this invention is to provide a process of resoling shoes obviating the disadvantageous features of the processes previously referred to and which will result in a bottom construction which combines strength with neatness of appearance.

Another object is to provide a sole adapted particularly for employment in the process referred to.

Further objects will appear from the detail description taken in connection with the accompanying drawing, in which—

Figures 1, 2, and 3 are perspective views showing successive steps in resoling a shoe in accordance with this invention;

Figure 4 is a section on the line 4—4 of Figure 10 3; and

Figure 5 is a detail of the sole.

Generally stated, in accordance with this invention, a shoe is provided having part, and more particularly the forepart, of its sole replaced by a sole part provided with an extension overlying the adjacent part, and more particularly the shank part, of the sole. In accordance with one embodiment of this invention, the worn part of the shoe bottom, which is generally the forepart, is removed and the end of the unremoved part, which is usually adjacent the ball, is chamfered. A sole part having an extension of reduced thickness is then laid on and secured to the shoe, as by stitching, and joined to the adjacent remaining part of the original sole, as by chamfering

and fastening; the extension is then laid over the adjacent or shank part and cemented down or secured in any other suitable manner.

Referring to the accompanying drawing and more particularly to Figure 5, the sole comprises a forepart 1 and a shank part 2 of reduced thickness. The sole may be constructed by partially splitting a piece of full thickness, the split being preferably carried inward as shown at 3, and the part therebelow being skived or chamfered, as shown at 4. If desired, the edge of the forepart may be channeled, as shown at 5. In half soling a shoe, the outsole is removed, as by cutting the stitches 13 securing a part of the old sole to the upper and insole, as shown in Figure 1, so as to expose the insole 6 and the inwardly-turned edges of the upper 7. The outsole is removed to any suitable extent, but it is preferable to terminate the removed part just back of the ball. The shank part 8 of the outside is then skived or chamfered, as shown at 9. A prepared sole 1, as shown in Figure 5, of the desired thickness is now placed on the shoe in the position shown in Figure 2, with the shank part 2 folded back, the channel flaps 5, if employed, having been previously turned back. In this position the chamfered parts 4 and 9 will match, and they can be secured in any suitable manner, as by cementing, nailing or stitching; even where cementing is resorted to, it is preferable to provide temporary tacks, as shown at 10, as well as a tack along the forepart, as shown at 11; these tacks may, however, be permanent. A line of stitches 12 is now run around the shoe, and where the shoe is the McKay type, having an insole 6, the stitches are run through the sole 1, the edges of the upper and the insole 6. If desired, the line of stitches 12 may terminate at the chamfered parts 4 and 9, or include the same, or run to the end of the sole at the heel 14. After the stitching operation has been completed, the shank part 2, as well as the channel flaps, is cemented in place as shown in Figure 3.

It will, therefore, be seen that the invention accomplishes its objects. A process is provided whereby a shoe may be resoled in a simple and convenient manner. While the new sole is firmly attached to the shoe and joined with the sole part at the shank, the sole part or flap 2, cemented as it is to the sole part remaining on the shoe, provides not only a neat appearing bottom construction, but also one having great strength. This is due to the fact that the outer layer of the sole 1—2 is uninterrupted, and as this layer is placed under tension during flexing of the

shoe, it provides the greatest strength where needed.

While this invention is particularly applicable to the general type of shoe specifically shown and described, it will be understood that the invention is applicable to other forms and types of boots as well as shoes. Thus, in the half soling of a welt shoe, the sole is removed at the forepart, leaving the welt as well as the insole and upper.

10 The sole 1-2 is then laid on and joined with the old sole in the same manner as shown in Figure 1. The stitching in this case can, however, be performed on the usual welt stitcher with the line of stitches passing through the welt 15 and sole part 1. The operation of pasting down the flap or sole part 2, as well as the channel flaps, where employed, can be proceeded with as before. As the extension 2 can be made thin, whether the sole 1-2 is employed in resoling a 20 McKay or welt shoe, the sole of the resoled shoe can have substantially the thickness and appearance of the original sole throughout. Moreover, since the grain of the leather can be on the outside, the bottom can be polished to provide a neat appearance and great strength where the soles overlap.

It will, furthermore, be understood that certain features, operations and sub-combinations are of utility and may be employed without reference to other features, operations and sub-combinations; that is contemplated by and is within the scope of the appended claims. It is, furthermore, obvious that various changes may be made in details and operations within the scope of the appended claims, without departing from the spirit of this invention. It is, therefore, to be understood that this invention is not to be limited to the specific details and operations shown and/or described.

40 Having thus described the invention, what is claimed is:

1. The process of resoling shoes, comprising, replacing the worn part of the shoe bottom by a sole-part having a long rearward extension of reduced thickness, joining the sole-part to a part of the original sole adjacent the worn part and laying the extension over the adjacent part beyond the joint.

2. The process of resoling shoes, comprising, removing a part of the old sole, laying on that part of the shoe bottom a sole-part having a long rearward extension, joining the sole-part with an adjacent part of the old sole and laying the extension over the joint thus formed.

3. The process of resoling shoes, comprising, removing the forepart of the old sole, replacing the same with a sole-part having a long rearward extension, joining the sole-part with the shank-part of the old sole and laying the extension over the shank-part and the joint.

4. A resoled shoe, comprising, an upper, a shank-part sole, and a forepart sole joined to the shank-part sole and having a long rearward extension overlying the shank-part and the joint.

5. A shoe sole having a long rearward extension of reduced thickness beyond the sole body, said extension being separated from said sole body forwardly of the terminus thereof.

6. A shoe sole having a long rearward extension of reduced thickness beyond the sole body, said sole body terminating in a chamfered part and

said extension being separated from said sole body above said chamfered part.

7. A shoe sole having a forepart of full thickness and having a long shank part of reduced thickness, the part of full thickness terminating at the shank and separated from the forepart forwardly of the terminus thereof. 80

8. A shoe sole having a forepart of full thickness terminating in a chamfered part and having a long shank part of reduced thickness separated from the forepart above said chamfered part. 85

9. The process of resoling shoes, comprising, replacing the worn part of the shoe bottom by a sole-part having a continuous tread surface and a lip extending from the reverse side thereof, joining the lip to an adjacent part of the original sole, and laying the tread surface over the joint to conceal the same. 90

10. A resoled shoe comprising, a repair sole having a body portion, a joint securing the body portion to a part of the original sole, and an extension from and integral with the body portion concealing the joint. 95

11. A resoled shoe comprising, a repair sole having a body portion with a chamfered part, an original sole part having a chamfered portion, a joint securing the chamfered sole parts together and an extension from and integral with said body portion concealing said joint. 100

12. A resoled shoe comprising, a repair sole having a body portion, a joint securing the body portion to a part of the original sole, and an extension from and integral with the body portion overlying the joint and extending to the heel breast line. 105

13. A resoled shoe comprising, a repair sole having a body portion, an original sole part terminating in abutting relation to the body portion of the repair sole, and an extension from and integral with the body portion forming therewith a continuous tread surface bridging the abutting ends of the body portion and original sole part and overlying the original sole part. 115

14. A resoled shoe comprising, a repair sole having a body portion secured to original shoe parts by stitching, an original sole part terminating in abutting relation to the body portion, and flaps extended from the body portion forming a continuous tread surface overlying the stitching and the abutting ends of the body portion and original sole part. 120

15. A resoled shoe comprising a repair sole having a body portion secured to original shoe parts by stitching, an original sole part terminating in abutting relation to the body portion, and flaps extended from the body portion forming a continuous tread surface overlying the stitching, original sole part, and the abutting ends of the body portion and original sole part. 125

16. The method of forming a repair sole for a shoe comprising cutting out from an integral piece of material of substantially the same thickness throughout, a whole sole of the desired shape and cutting away more than half the thickness of the rear portion of said sole, said cut-away portion extending from the shank portion to the end of said sole, and cutting off a small portion of the rear end of the front portion of said sole, said cut tapering towards the rear end of said front portion. 130
